UNITED STATES PATENT OFFICE

JOHANNES SJÖSTRÖM, OF GÄVLE, SWEDEN

DOOR CLOSER

Application filed October 20, 1931, Serial No. 569,983, and in Sweden November 7, 1930.

This invention relates to improvements in door closers and checks of the kind adapted to be used on a right hand as well as on a left hand door without rearrangement of its internal mechanism, said door closers comprising a spring located inside the housing of the closer, said spring being connected to two rotatably arranged spring-holders for actuating the spring alternatively and secured 5 against rotation in more than one direction, besides which there is located a central spindle being at one end connected to a checking mechanism and at the other end to a closing arm, which is to be secured to the door frame 10 or the like and is adapted to actuate the spindle and the spring holders when the door is being opened or closed.

The purpose of the present invention is to effect an improved and simplified device in such door closers. One object of the invention is the arrangement of the spring holders in such a way that they can be easily taken out, exteriorly reached and operated and be very reliably guided. In consequence of this 20 object a screw-spring is substituted for the helical springs generally used in door closers of the kind in question, said screw spring having its ends fixed to each of the spring holders.

These features together with other features 30 of the invention will be hereinafter described, reference being had to the accompanying drawings.

In the drawings,

Figure 1 is a sectional view of a door check 35 and closer showing an embodiment of my invention,

Figure 2 is a plan view, the closing arm being shown in dash-and-dot-lines.

Figure 3 is a sectional view taken on the 40 line III—III of Figure 1 and

Figure 4 is a sectional view taken on the line IV—IV of Figure 1; and

Figure 5 is a detail perspective view showing 45 the interlocking connection between the neck and sleeve.

In the drawings I have shown a housing 1 in which the spring mechanism is arranged and a cylinder 2 disposed at right angles to said housing and integrally made therewith and with sidewings 3 located on the hous-

ing, said wings having screw holes for securing the device to the door. Into the wall between the housing 1 and the cylinder 2 there is screwed a sleeve 4, said sleeve together with a neck 5, extending upwards in the housing, surrounding the centrally located spindle 6 and forming a bearing for said spindle the said bearing box having in its upper part suitable tightening elements such as packings. The spindle 6 extends downwards into the cylinder 2 and is provided with a crank 7, being connected to the common checking piston 9 by means of a pitman 8.

The sleeve 4, facing the housing 1 is provided with a shoulder 10 for carrying an annular flange 11 rotatable on the said shoulder, said flange having an upwardly extending neck 12, surrounding partly the neck 5 of the bearing sleeve 4 and partly the spindle 6 by means of the part extending above the said sleeve, said neck 12 being at its outer end provided with a collar 13, through which the spindle extends. The annular flange 11 is provided with a stamped out portion 14, in the form of a tongue or the like in which the one end of a screw spring 15 is fixed, in a suitable manner, said spring, running from a point of the flange 11 located outside the stamped out portion 14 of the outer part of the flange.

It may also be imagined that the support of the spring is located at the outer part of the flange 11 and that the spring is fixed to the said part by means of its double-folded end. Further the flange 11 is at its circumference provided with a member of stages 16, steplike arranged to support the spring. At the inside of these stages there are projections 17 to prevent the spring from being pulled towards the centre when the spring is being strained. The said projections may be arranged at another suitable point of the flange. Further the flange 11 has a downwardly directed stopping arm 18, projecting from the outer portion of the flange and normally resting against a shoulder 19 located in the wall of the housing 1.

In the upper part of the housing 1 a second annular flange 20 is rotatably journaled embracing with its inwardly turned neck 21 the

upper part of the neck 12, the said neck 12 thus forming a bearing for the neck 21. The flange 20 is provided with a fastening device 22 for the other end of the spring 15, support 23 and projections 24 for the same, corresponding to similar arrangements on the flange 11. Moreover the flange 20 is provided with a projection 25 (Figure 3) normally resting against an upwardly projecting shoulder 26 from the upper part of the housing 1. Hereby it may be observed that the spring support 22 and the ratchet 25, 26 are arranged about diametrically in the housing relatively to corresponding devices 14 and 18, 19 respectively on the inner flange 11, and that the shoulder 19 and the shoulder 26 are thus arranged relatively to the stopping arms or shoulders 18 and 25, that the flanges 11 and 20 are adapted to be rotated only in a direction, which is opposite to that of the other.

The housing 1 has a cover 27, provided with a central opening for two ratchet wheels, one inner (upper) wheel 28 and one outer (lower) wheel 29. The inner ratchet wheel 28 is journalled on the spindle 6 and the outer ratchet wheel 29 is journalled in the cover of the housing. The lever 30 for actuating the device, which is in a known manner connected to the frame or the like of the door, is fixed on to the upper end of the spindle and is provided with a double pawl 31, pivotally secured to the same, the upper arm 32 being intended to engage the ratchet wheel 28 and the lower arm 33 to engage the ratchet wheel 29.

The inner ratchet wheel 28 is provided with a neck 34 extending into the housing, the end portion 35 of said neck being shaped as an inwardly directed annular flange surrounding the spindle 6, said flange having a dimension approximately corresponding to the collar 13 of the flange 11 and being provided with a pin 36 engaging a hole of the said collar. The outer ratchet wheel 29 has also a neck 37 extending into the housing 1, said neck being journalled on the neck 34 and supported by the annular shoulder 20' of the neck 21 of the flange 20, said part surrounding the spindle 6 being interlocked with the said neck by means of a pin or the like 38 engaging a seat 39 in the shoulder 20'. It is evident that the necks of the two ratchet wheels may, in another suitable way than the one described, be connected to the necks of the flanges 11 and 20.

When using the closer on different doors one or the other of the arms 32, 33 of the double pawl 31, owing to, if the door is a right hand or left hand door, will engage the opposite ratchet wheel 28, 29. If the closer is mounted on a right hand door it is evident that, because the closing arm 30 is swung to the right when the door is opened, 65 the inner spring holder or flange 11 will

turn by the aid of the ratchet wheel 28, by which the spring 15 will be pressed together. The outer end of the spring is hindered hereby from moving, the outer spring holder or flange 20 not being able to rotate on account of the projection 25 engaging the shoulder 26. If the closer is mounted on a left hand door, the closing arm 30 will turn to the left when the door is opened, at which the arm 33 of the double pawl 31 will engage the ratchet wheel 29, and thereby turning the outer flange 20 around the upwardly extending neck 12 of the inner flange; during this operation the inner flange 11 is kept in its position by the stopping arm 18 resting against the shoulder 19, the spring 15 being pressed together. When the door is being opened the spindle 6 will, on account of the movement of the closing arm, turn and influence the checking mechanism in a known manner, and when the door is being closed by the effect caused by the spring force this movement is being regulated by the checking mechanism also in a known manner.

It is evident that the construction of the closer will make it easy to reach the inner parts of the same and will effect a reliable guiding of the parts of the mechanism actuating the spring. Moreover an intermediate part, specially arranged between the two spring holders in order to influence the same, will become unnecessary. The highly projecting neck 12 of the inner spring holder 11 will make possible the arrangement of a high neck 5 on the box 4, the said box thus obtaining a greater capacity of preventing leakage around the spindle 6.

Having now described my invention, what I claim as new and desire to secure by Letters Patent is:

1. A door closer comprising a housing, a helical spring in the housing, a bearing box extending into the housing, a spindle journalled in the bearing box, a closing arm fixed to the spindle, upper and lower flanges in the housing, means for securing the respective terminals of the spring to the flanges, a neck carried by the lower flange confining the bearing box, a neck carried by the upper flange and journalled on the neck of the lower flange, and means connected with the respective flanges for stressing the spring reversely upon movement of the closing arm in reverse directions.

2. A door closer as claimed in claim 1, wherein means are provided to interlock the respective flanges with the housing to prevent simultaneous movement of the flanges during swinging of the closing arm.

In witness whereof I have hereunto signed my name.

JOHANNES SJÖSTRÖM.
